UNITED STATES PATENT OFFICE.

ALEXANDER LEVIN, OF CHICAGO, ILLINOIS.

LUMBERMAN'S APRON.

SPECIFICATION forming part of Letters Patent No. 396,282, dated January 15, 1889.

Application filed June 15, 1888. Serial No. 277,263. (No model.)

To all whom it may concern:

Be it known that I, ALEXANDER LEVIN, a citizen of the United States of America, residing at Chicago, in the county of Cook and State of Illinois, have invented certain new and useful Improvements in Lumbermen's Aprons, of which the following is a specification, reference being had therein to the accompanying drawings.

10 This invention relates to improvements in leather aprons as used by lumbermen, teamsters, &c., and generally suspended and secured to the body by a neck-strap and a waist-strap. With these aprons, from the inclining positions of the wearer, the neck-strap is liable to slip upward against the head and thereby to become inconvenient, and it has been the object of this my invention to obviate such sliding; and with that object in view 15 my invention consists of an elastic strap connecting the neck-strap with the waist-strap in a manner to hold such neck-strap in the desired position close to the shoulders without impeding the movements of the wearer, 20 all as will be more fully hereinafter described and specifically claimed.

In the accompanying drawings, Figure 1 represents the apron as worn by a man, and Fig. 2 a perspective view of the apron detached.

25 Corresponding letters of reference in both figures of the drawings designate like parts.

A denotes the apron, generally of leather, with the part protecting the lower body made wider than the part protecting the breast of the wearer.

30 B is the neck-strap, secured to the upper

corners of the apron and provided with a buckle for lengthening or shortening it; and C is the waist-strap, secured with one end to one side of the apron, while its opposite end will 40 engage with a buckle, c, secured by a short strap to the other side of the apron.

D is a back-strap, made of any kind of elastic material and having a loop, d, to each end, which loops of the opposite ends are passed 45 over the neck-strap B and waist-strap C to couple both in a manner holding them a proper distance apart and thereby preventing the neck-strap from leaving its position close to the shoulders. The back-strap D, by its elasticity, at the same time will accommodate itself to the varying positions the wearer may have to assume during his work without discomfort to him.

50 What I claim is—

1. The combination, with a lumberman's apron having neck-strap B and waist-strap C, of an elastic back-strap, D, connecting both straps B and C, substantially as and for the purpose set forth.

2. The combination, with a lumberman's apron having neck-strap B and waist-strap C, of an elastic back-strap, D, provided with loops to its ends for coupling the straps B and C, substantially as and for the purpose set forth.

55 In testimony whereof I affix my signature in presence of two witnesses.

ALEXANDER LEVIN.

Witnesses:
